HAY LOADING DEVICE

Delno O. Warner, Thompson Township, Delaware County, Ohio

Application July 31, 1937, Serial No. 156,711

7 Claims. (Cl. 214—81.5)

This invention relates to a hay-loading device and particularly to a draft element or tongue for a wagon provided with means for dividing the load.

Broadly stated, the principal object of the invention is to provide a draft element for a wagon of this type, so arranged and combined with the wagon that the source of power, whether horses or tractor may be used for moving a portion of the load from the rear of the wagon to the front thereof.

A further object is to provide automatic chocking means for holding the wagon against forward motion at the time the part load is being moved to the front and for automatically moving such chocking means to inoperative position when not needed.

Other objects including the attainment of cheapness and simplicity will be in part apparent and in part pointed out hereinafter in connection with the accompanying drawings wherein Fig. 1 is a fragmentary elevational view, partly in section, of a hay-loading device embodying the invention; Fig. 2 is a plan view of a portion of the structure shown in Fig. 1, indicating the hay receiving superstructure in phantom view and showing the relatively movable parts in close coupled relation; Fig. 3 is a similar plan view showing the relatively movable parts in partly extended relation, a position assumed during the process of moving a part load of hay to the front; Fig. 4 is a fragmentary vertical section through the superstructure or hay-receiving portion of the wagon and showing the connection of the flexible element employed for moving the part load of hay forward; and Fig. 5 is a fragmentary front elevation of the structure shown in Fig. 4.

In the drawings, the numeral 10 indicates the front wheels of a wagon of usual four-wheeled construction having the usual axles, the front one of which is indicated at 11, the usual coupling element between the front and rear axles (not shown) and the usual bolsters 12 adapted to support the wagon superstructure, in this case a hay-receiving body or frame indicated generally by the numeral 13.

The frame 13 comprises suitable longitudinal members 14, transverse members 15 and floor 16. Extending above the floor 16 at the edges are guide elements 17 adapted to guide an auxiliary frame indicated generally by the numeral 18. The auxiliary frame 18 comprises longitudinally extending elements 19 carrying cross members 20, a short rear transverse upright 21 and front

retaining posts 22 suitably braced by elements 23 and carrying a transverse element 24. In front of the posts 22 is a transverse element 25 through which extends an attaching element 26 for a flexible cable 27 extending forwardly and used for the purpose of pulling the auxiliary frame 18 to the front end of the hay frame after it has received a part of the load while located at the rear of the frame.

Pivoted to the front axle by a pin 28 is a casting 29 which is provided with a downwardly extending bolt 30 receiving steering rods 31 which extend to the steering knuckles 32 controlling the wheels 10. Pivoted to the casting 29 at the point 33 is a pipe 34. When the casting 29 is designed for reception of a pipe larger than the pipe 34, it may be adapted to a smaller pipe by means of the short section 35. Secured to the casting 29 by means of straps 36 is a casting 37. The same pin 38 may pass through the straps 36, the pipe 34 and the pipe section 35. Means may be provided if desired to cause the straps 36 to pivot with the pipe 34 whereby the casting 37 will always remain centered with respect to pipe 34. This, however, I have found can be obviated by providing a flare at the forward end of the casting 37, as indicated at 39. The casting 37 is provided on its upper surface with a detent retaining means 40 and guide ribs 41 adapted to guide the detent into engagement with the element 40.

Telescoping on the pipe 34 is a larger pipe 42 which extends forwardly and has a neck yoke 43 connected thereto, the neck yoke 43 may be rigidly connected to the pipe 42, although I prefer that it be so connected thereto as to be somewhat yielding or semi-rigid.

Rigidly secured to the pipe 42 in any suitable manner, as for example set screws not shown, is a casting 44 provided with suitable means such as a bolt 45 for securing a suitable hitch or evener 46 for horse draft. It is to be understood that the invention is not confined to a horse draft appliance but that the pipe 42 may, if desired, be secured to a tractor. Pivoted to suitable gears 47 by means of a bolt 48 is a detent 49 adapted to cooperate with a detent retainer 40 on the casting 37. The detent 49 carries an eye 50 to which the flexible element 27 is secured. The detent 49 is also provided with a spring 51 adapted to urge the same downwardly whereby to insure proper engagement between such detent and the element 40. I have found that the spring 51 can be omitted if desired.

Pivoted to suitable lugs 52 on the casting 29

is a chock 53 provided with a sharp point 54 and a suitable stock element 55 for limiting the amount which the point 54 may dig into the ground. This element may be adjustable any length if desired. Slidable on the pipe 34 is a collar 55 having an eye 56 or other suitable means for attachment of a flexible cable. Carried by the casting 37 is an eye 57 through which passes a flexible element 58 secured to the eye 56 and to another eye 59 carried by the chock 53 at a point spaced from its pivot point. Secured to the bottom of the casting 44 is a guard 60 adapted to support the short point 54 when the chock 53 is in inoperative position.

15 In starting the operation of this device, the draft element or tongue is close coupled to the position shown in Fig. 2 and the auxiliary frame is moved to the extreme rear of the hay frame 13, the flexible element 27 being of a proper length 20 to permit this positioning of parts. Preferably the element 27 will have very little slack when the parts are so positioned. Any usual type of hay loader is attached at the rear of the wagon and the rear half of the wagon, that is the auxiliary frame 18, is loaded in the usual manner. Having loaded the auxiliary frame 18, the driver or operator pulls the flexible element 27 whereby to disengage the detent 49 from the element 40 and then causes the source of power, whether a 30 team or a tractor to move forward. The forward motion soon takes up the slack in the element 27 and releases the collar 55 allowing it to move forwardly whereby to drop the chock 53 into operative position. When the source of power has moved forwardly a distance sufficient to 35 lower the chock 53 into ground engaging position, it will begin to move the auxiliary frame 18 forward. Forward motion of the source of power, causing the pipe 42 to move with respect to the pipe 34, will result in moving the frame 18 to the forward end of the frame 13. When this position has been reached, the team or tractor is caused to move rearwardly thereby restoring the parts to original position, that is, causing the 45 detent 49 to be engaged over the element 40 and the chock 53 to be elevated to the position behind the shield 60. The device is again operated to load the portion of the frame 13 behind the auxiliary frame with the second half of the load 50 whereupon the load is unloaded by any well known method and the auxiliary frame 18 moved to the rear of the frame 13 for repetition of the operation described.

While I have shown and described the present 55 preferred embodiment of my invention, I wish it understood that the same may be realized by different structures and that I am not limited to the details of the disclosure but only in accordance with the appended claims.

60 Having thus described my invention, what I claim is:

1. In a device of the class described, in combination, a wagon and a hay frame carried thereby, said hay frame comprising a lower frame element and an upper frame element longitudinally 65 slidable with respect thereto, said upper frame element when moved to its forwardmost position exposing said lower frame element sufficiently to receive one portion of a divided load, said wagon

including an extensible draft element extending forwardly and comprising portions slidable relatively to each other, one of such portions being attached to the wagon chassis and the other being attached by a flexible connector to the said upper frame element, and disengageable means for holding the two portions of said draft element in close coupled relation.

2. In the combination recited in claim 1, chock means for preventing forward motion of the wagon and means operated by extension of the draft element for moving said chock means from inoperative to operative position and operated by return of the relatively movable portions of said draft element to close coupled position for returning said chock means to inoperative position.

3. In the combination recited in claim 1, chock means for preventing forward motion of the wagon and means operated by extension of the draft element for moving said chock means from 20 inoperative to operative position and operated by return of the relatively movable portions of said draft element to close coupled position for returning said chock means to inoperative position, and shield means carried by said draft element 25 and positioned in front of said chock means when the same is in inoperative position.

4. In a device of the class described, in combination, a wagon comprising chassis, and a draft element comprising a tongue for horse draft, a 30 hay frame carried by said chassis and having a short auxiliary frame slidable back and forth from front to rear thereof, said tongue comprising telescoping parts one of which is attached to the wagon and the other of which is movable and 35 provided with hitching means for horse draft, cooperating means carried by said telescoping parts for releasably connecting them in close coupled relation, and a flexible element connected to the movable telescoping part and to the auxiliary 40 frame.

5. In the combination recited in claim 4, chock means for preventing forward motion of the wagon and means operated by extension of the draft element for moving said chock means from 45 inoperative to operative position and operated by return of the relatively movable portions of said draft element to close coupled position for returning said chock means to inoperative position.

6. A wagon tongue for the purpose described 50 comprising, in combination, front and rear parts having telescoping elements, said rear part being adapted to be connected to a wagon and being provided with detent receiving means, said front part being adapted for attachment to a source of 55 power, detent means carried by said front part and adapted to be releasably engaged with said detent receiving means and a flexible cable connected to said detent means and adapted to extend rearwardly to said wagon.

7. In the combination recited in claim 6, a chock pivoted to said rear part, a collar slidable on the rear telescoping element and adapted to be engaged by said front part, an eye carried by said rear part in advance of said collar and a 65 flexible element secured to said collar, passing through said eye and secured to said chock at a point spaced from said pivot point.

DELNO O. WARNER.
